UNITED STATES PATENT OFFICE.

HAROLD M. PLAISTED, OF ST. LOUIS, MISSOURI, ASSIGNOR OF FORTY-NINE ONE-HUNDREDTHS TO WILLIAMS PATENT CRUSHER & PULVERIZER COMPANY, OF ST. LOUIS, MISSOURI, A CORPORATION OF MISSOURI.

FINE GRINDER.

1,418,735.

Specification of Letters Patent. Patented June 6, 1922.

Application filed March 21, 1919. Serial No. 283,977.

To all whom it may concern:

Be it known that I, HAROLD M. PLAISTED, a citizen of the United States, residing at St. Louis, State of Missouri, have invented 5 certain new and useful Improvements in Fine Grinders, of which the following is a specification.

This invention relates to certain new and useful improvements in fine grinders the 10 peculiarities of which will be hereinafter fully described and claimed.

The main object of my invention is the provision of means for fine grinding to a desired degree of fineness of total reduction, 15 drawing off the finished product as fast as it is made, regulating the fineness, and operating with minimum resistance to the hammers and with consequent reduction of power.

20 In the accompanying drawing on which like reference letters indicate corresponding parts, Fig. 1 represents a vertical sectional elevation across the shaft of a grinder exemplifying my invention; Fig. 2 a vertical 25 sectional elevation of said machine taken on the line 2—2 of Fig. 1; Fig. 3 a side elevation of said machine with the shaft bearing removed and part of the housing of said bearing in section; and Fig. 4 a front 30 view of said grinder with part of the casing broken away to show the breaker plate.

The letter A designates a rotor shaft driven by a pulley B and mounted in suitable bearings, such as ball bearings shown 35 in Fig. 2, secured in a ring housing C contained within a clamp D carried by the side housing E of a grinder of suitable construction.

On the shaft A are mounted discs F, in 40 which are pivotally mounted stirrup hammers having legs G provided at their inner ends with holes for pivot bolts H passing through holes in said discs F. The said legs are connected by a cross bar, forming 45 the head C' of the hammer the outer surface I of which forms part of a cylinder and is described by an arc the center of which is the pivot point of support for said hammer. The inner surface J of the cross bar is like- 50 wise convexed preferably, but reversely curved, and the inner surface and outer surface or faces of the cross bar, or head C' meet each other at intersecting lines forming cutting edges K K' at equal distances

from a radial line through the pivot point. 55 A double convex section is thus formed of considerable thinness radially, relative to its breadth from edge to edge, whereby the hammer head C' formed by this cross bar is practically all edge at front and rear; in 60 other words, it does not present to the material within the grinder a blunt face, as in the usual form of hammers, but on account of its relative thinness radially and the lenticular form of cross section it passes 65 through the material with minimum resistance, and consequently requires comparatively little power to effect the rotation of a rotor having this form of hammer.

A breaker plate L is mounted in a pocket 70 L' formed in the front of said casing, with openings m at the sides whereby the breaker plate may be slipped into said pocket from one or either side. The length of the breaker plate is practically the width of the 75 housing, and therefore the ends of the breaker plate bear upon the edges of the openings in the sides of the housing. If desired the upper edge of the plate may have a lip l fitting a matching opening or groove 80 in the top of said pocket.

Cooperating with said breaker plate is a cage M, preferably solid and without openings, and fitting in corresponding openings in the side housing of the grinder. The 85 cage is nearly semi-circular, as shown in Figs. 1 and 2, and a tapered key O is driven in from one or both sides of the housing into the clearance space between the adjacent edges of the breaker plate and cage, whereby 90 the plate is forced upward and the cage is forced downward, and both are firmly held in operative position.

The hammers are so mounted that their outer faces I are in close proximity to the 95 cage M along a line in said face parallel to the shaft. Since the outer face is cylindrical about a shorter radius than the grinding face of the cage, this face I will present a wedge-like opening from the forward 100 cutting edge K to a radial line or plane through the center of the shaft and pivot point of support; that is, the wedge-shape opening between the outer face I and the grinding surface of the cage M will allow 105 the entrance of the coarse feed, and by the wedging action, cause the pivoted hammer to be retarded and thus crush the inter-

posed feed material between the face I and the cage as indicated in Fig. 1. Any material that is not thus wedged between the crushing surfaces, passes over the inner 5 face of the hammer and is met by the following hammer. It will be noted that there is always a line in the outer face I parallel to the shaft, that is in close proximity to the grinding cage, and that that line or element 10 in the face shifts back and forth from the center of the face to the forward point under the action or retarding influence of the material wedged between the cage and said outer face. Thus the jaw action or jaw 15 crushing action, is obtained by the rotary pivoted hammers and their outer cylindrical faces in connection with the cage in close proximity to the hammer circle. While I have shown the cage as solid, it may be other- 20 wise formed, and I have shown in Figs. 1 and 2 a hammer head having openings P preferably parallel to the radial plane and extending from the outer face I to the inner face J with increasing size or distance be- 25 tween the passages, whereby clearance passages are formed for the relief of the material being crushed at the outer face. This material, thus crushed, will pass through said passages, as indicated in Fig. 1 30 by the fine material. This open bar construction of the cross bar head C' of the hammers acts in substantially the same way as a cage with open bars,—that is, the material being crushed is released from the crush- 35 ing area and thus avoids clogging of the hammer and cage with surplus material or material already ground to the proper degree of fineness.

It is now my aim to withdraw such finished product from the grinding cage and action of the rotor, and this I do by the construction shown in Fig. 1, in which a back wall Q is provided with a passageway R near the junction of the curved top S; 40 and side walls T combine with said top and back wall and a bottom U of a hopper V, to form a receiving chamber X back of and partly below said hopper. The wall U of said hopper is inclined and preferably tan- 45 gent to the hammer circle, and is provided on its lower end with a grinding plate W concentric with the shaft A. The upper end of said bottom is hinged or pivoted at 3 adjacent to the top S so that the lower end 50 with its grinding plate W may be adjusted to and from the hammer circle by means of rods 4, each having one end secured to the bottom end of the hopper bottom U and the other end passing outward through open- 55 ings in the outer wall 5 of said hopper, and having jam nuts 6 by which the rod 4 is firmly held by a stirrup frame 7 from the front wall of the hopper casing. The joint between the curved top S and the hopper 60 bottom U is filled with a fibrous or flexible 65

material 8, so that the slight movement at and near the hinge will not cause an opening. The reason of this is, that a lateral exhaust chamber 9 is formed by walls back of and adjacent to the curved top S and a communicating passage from said lateral chamber connects with said opening R in the back wall Q. This lateral chamber 9 and passage 10 which is a continuation of the passageway R are connected by pipes 11, preferably 70 at each end of said chamber 9, to a fan exhaust or other suction means not shown. A certain amount of air will enter with the feed through the hopper V but it is desirable to provide a regulated air inlet by which 75 the quantity of air, depending upon the weight of the material being ground, may be varied. This is effected by providing a closing plate in duplicate having matching holes. The inner plate 12 is divided in half 80 through the axis of the shaft, and is preferably circular and a little larger than the opening 13 in the side housing or the casing of the grinder so it will overlap said casing as shown in Figs. 2 and 3. The lower half 85 of the plate preferably fits in groove 14 in the lugs 15 of said housing clamp D, and the outer plate 16 is somewhat smaller in diameter so it will fit between said lugs 15 as shown in Fig. 3 and be readily rotated by 90 means of a handle 17 at the periphery of said plate, preferably formed by the turned-out end of the splicing strip 18 fastening together the halves of said outer plate. Holes 19 and 20 are provided in the outer 95 and inner plate respectively, and the rotation of the outer plate will vary the effective opening for air inlet. The opening 13 in the side of the casing is slightly larger than the diameter of the discs F which are 100 mounted directly adjacent to said openings and practically close the casing to the exit of material. In these discs are likewise provided holes 21 as near the center as practicable, by which the air admitted through 105 the side closing plates with their regulated openings passes to the center of the rotor between the discs at both sides. This interior space between the discs is filled with material being ground, and the finer or finest 110 particles will be carried upward by the suction of the air entering through the regulated openings 19 and 20, and through the disc openings 21, and pass upward along the tangential wall Q of the chamber above the 115 rotor under the combined influence of air suction and the rotation of the hammers. As the material is driven and sucked upward past the opening R the finer particles are drawn off through the passage 10 into 120 the lateral chamber 9 and outward through the pipes 11. The coarser particles under the impulse of the hammers are driven past said opening R and impinge on the curved top S, and are directed downward again by 125 130

the hopper bottom U for further grinding action by the hammers, and especially by the fine grinding plate W that is closely adjusted to the hammer circle.

5 The chamber X above the rotor as thus described, is preferably provided with inclined partitions 22 and 23 nearly parallel to the hopper bottom U, and having on their bottom ends grinding plates or other concaves 22' and 23', substantially concentric with the axis of the rotor. These bottom ends are provided with side extension lugs 24, fitting in matching grooves 25 in the sides of the casing, which casing is spaced 10 nearer together above the rotor than below the center of the rotor, so that said grooves 25 are open at the bottom for receiving said lugs 24. A sliding adjustment of said partitions and grinding plates is effected by 15 means of rods 26, preferably fastened at their upper end and passing outward through the curved top and having on their threaded outer ends adjusting nuts 27, mounted in slotted extensions 28 from the 20 top of the casing. Since the grinding plate W is substantially tangent to the hammer circle at one side of the rotor, the partitions 22 and 23 provide return passages for the coarser material driven upward by the hammers, which passes around the upper ends 25 of the partitions which do not extend upward to the curved top but leave a space as shown in Fig. 1. The coarser particles are therefore deflected by the curved top over 30 the edge of said partitions and pass downward again to the rotor, and are delivered to the hammers as they pass below the lower end, and crush between the grinding concaves and the hammer faces I. The outlet 35 or lower ends of said passages are reduced in size as shown in Fig. 1, so as to deliver the returning stream of particles in a thin line across the faces I of said hammers.

The hopper bottom U is provided with an 40 adjustable slide 29, by which the outlet or throat V' of the hopper V and therefore the entrance of the material to the rotor is regulated. It will be observed that the hinge or swinging adjustment of the hopper bottom U, does not prevent the adjustment of the cut-off slide 29 mounted thereon, as suitable slots are provided opposite the adjusting rods 4 at the sides of said plate.

By means of the wider spacing of the 45 sides of the casing below the center and the projections formed by said sides being nearer together above the rotor, I am able to slide the projecting lugs 24 of the grinding plates 22' and 23' with the partition plates and 50 adjusting rods attached thereto, upward into sliding engagement with the grooves 25 in the sides of the casing. Other operative means for adjusting said grinding plates and partitions may be employed.

55 The duplicate closing plates 12 and 16 in

the sides are retained in position by clips 30 as shown in Fig. 3. The back or rear end of the cage is also provided with an adjustment, such as screws 32 passing through the back wall and engaging the cage, whereby 70 the adjustment of the screws from outside will force the rear end of the cage inward toward the hammer circle and take up the clearance space that is shown in Fig. 3 on the inside of the cage. This adjustment and 75 therefore the space at the back end of the cage, is very slight and barely more than is necessary to bring the rear end of the cage into contact with the hammers or tangent to the hammer circle. Slight as this adjustment may be, it will provide a fine grinding action at the rear of the cage similar to that of the concave grinding surfaces W, 22' and 23'.

The means for regulating the size of the 80 outlet R in the back wall of the main chamber is preferably in the form of a cut-off slide 31, provided with holes and pin for adjusting said slide to various positions across the passage 10. The smaller the 85 opening left by this regulating slide, the greater will be the velocity of the air that is sucked through this outlet of the main chamber by the exhaust fan or other means connected to the pipes 11 previously mentioned. The greater the velocity of this escaping air, the greater the influence upon the ground particles, especially the finer particles, passing upward along the back wall past the opening therein. The openings 19 and 20 communicating with the 90 openings 21 in the discs, admit any desired quantity of air to the inside of the rotor and consequently provide a regulatable quantity of air to correspond with the fineness and weight of the material being 95 ground and thus pneumatically removed from the grinder. In other words, a heavy material will require more air to carry it 100 upward and outward into the pipes 11 than a lighter material and the air inlet would be correspondingly large and the velocity of the air at the outlet of the main chamber would be regulated by the slide 31 to act 105 with best effect upon this heavy material.

On the other hand, a light material compared with the one just described, would allow of the reduction of the quantity of air by closing the regulating side plates more or less to give sufficient air to lift the 110 relatively lighter material, and then the slide 31 would be adjusted to secure the proper velocity of air at the outlet to suck out the fine particles of such light material from the main chamber, while leaving the 115 heavier particles of the same material to pass upward over the upper ends of the partition walls 22 and 23 and downward through the constricted openings and upon the grinding faces I of the rotating ham- 120

130

mers. Thus I have provided for varying both the quantity of air admitted to the casing and the velocity of the air escaping under suction from said casing, according to 5 the weight and fineness or either, of the material being ground.

I claim:

1. In a grinder provided with a cylindrical cage, having a rotor mounted therein, 10 hammers mounted in the rotor, said hammers terminating at their free ends in heads having convex inner and outer surfaces, said outer surface being disposed substantially tangent to the inner surface of the cage.

15 2. A fine grinder comprising a cylindrical cage, and rotary pivoted hammers mounted therein, each having a cross bar connecting two legs provided with holes for pivotal mounting,—said bar having an outer cylindrical face and an inner reversely curved face meeting the outer face in a cutting edge at each side of a radial line, and having radial openings between said faces forming 20 passages for the escape of material crushed 25 between said outer face and the cage.

3. In a grinder provided with a casing having therein a feed hopper, a rotor within 30 said chamber, a chamber above said rotor and within said casing for receiving ground material, means within the chamber for separating the finely ground material from the coarsely 35 ground material and returning the latter to the rotor, and grinding plates adjacent to the bottom of said chamber for further 40 grinding the returned material.

4. A fine grinder comprising a rotor hammer element, a hopper having an inclined bottom substantially tangent to said rotor hammer circle at the lower end and pivoted 45 near the upper end, a cut-off slide adjustably mounted on said hopper bottom, and means to adjust the lower end of said slide and hopper bottom to and from said hammer circle.

5. A fine grinder comprising a rotor, a 50 casing, a hopper having a bottom wall, a back wall side walls and curved top wall forming, in combination with said hopper bottom wall, a chamber above said rotor, inclined partition walls substantially parallel 55 to said hopper wall and provided with grinding concaves at their lower ends adjacent to the hammer circle and forming a series of return passages for the material deflected by the curved wall, and means extending outside 60 said chamber to adjust said partitions and grinding concaves with regard to said hammer circle.

6. A fine grinder comprising a rotor, a 65 casing having side and top walls forming a hopper and a main chamber below said hopper and above the rotor,—the back wall having an opening near the curved top,—walls forming a lateral chamber and communicating passage back of and adjacent to 70 said curved top, and connected by said

opening in the back wall with the main chamber, a regulating cut-off slide at said passage, and pipes under air suction connected to said lateral chamber.

7. A fine grinder comprising a rotor shaft, 70 discs thereon, stirrup hammers pivotally mounted on said discs, a casing having openings in the sides and air suction means communicating therewith,—said discs being mounted at said openings and practically 75 closing same to the exit of material, and having openings near the shaft for air inlet,—and side closing plates having adjustable openings for air inlet.

8. A fine grinder comprising a rotor, a 80 casing having its sides spaced nearer together above than below said rotor and grooves, open below, formed on the inside above the rotor, walls forming a chamber 85 above said rotor, slidable partitions having grinding plates provided with lugs mounted in said grooves, threaded rods extending from the top of said slidable partitions through the top of the casing and operable from outside the casing for adjusting said 90 partitions and grinding plate.

9. In a grinder provided with a cylindrical cage having a rotor mounted therein, hammers mounted in the rotor, said hammers terminating at their free ends in heads, 95 the outer surfaces of which are convex and disposed substantially tangent to the inner surface of the cage.

10. In a fine grinder, a rotor provided with hammers having heads of double-convex cross-section, said heads being perforated radially from the outer convex surface to the inner convex surface.

11. In a rotary grinder, a housing provided with a hopper, a cage co-operating with the housing, a breaker plate adjacent the throat of the hopper, a rotor, and a receiving chamber above the rotor, said chamber being provided with partitions, each of which terminates in a grinding plate adjacent the 110 rotor.

12. A disintegrating device, consisting of a concave having a rotor therein, said rotor having hammers with heads having convex outer and inner surfaces terminating in cutting edges, and said outer convex surface being on an arc of less radii than that of the concave.

13. In a grinder, a rotor provided with hammers having heads of double convex 120 cross-section and a shank having an opening for pivotal mounting, the radius of curvature of the outer convex surface being described from the shank opening, and the radius of curvature of the inner convex surface being substantially greater than that of said outer convex surface.

In testimony whereof I have affixed my signature.

HAROLD M. PLAISTED,
